UNITED STATES PATENT OFFICE.

JOHN H. O'DONNELL, OF WATERBURY, CONNECTICUT, ASSIGNOR TO THE WATERBURY MACHINE COMPANY, OF WATERBURY, CONNECTICUT, A CORPORATION OF CONNECTICUT.

WIRE-DRAWING MACHINE.

SPECIFICATION forming part of Letters Patent No. 738,932, dated September 15, 1903.

Application filed October 6, 1902. Serial No. 126,205. (No model.)

To all whom it may concern:

Be it known that I, JOHN H. O'DONNELL, a citizen of the United States, and a resident of Waterbury, county of New Haven, and 5 State of Connecticut, have invented certain new and useful Improvements in Wire-Drawing Machines, of which the following is a specification, accompanied by drawings.

My invention relates to wire-drawing machines; and its objects are to improve upon the construction of such machines and to increase their efficiency.

Another object of my invention is to obtain a combined compression of the metal on entering the die and a rotary movement between the metal and the die.

Further objects of my invention will hereinafter appear; and to these ends my invention consists in a wire-drawing machine for 20 carrying out the above objects constructed and arranged and having the general mode of operation substantially as hereinafter fully described in this specification and shown in the accompanying drawings, in which—

25 Figure 1 is a side elevation of a machine embodying my invention, shown partly in section. Fig. 2 is an end view of the same, partly in section.

According to my invention a compression 30 of the metal is obtained on entering the die, and there is a relative rotary movement between the metal and the die. According to my construction means are also provided for varying the relation between the speed of 35 feeding and the rotation.

Referring more particularly to the drawings, the grooved rolls E and I are mounted upon shafts D and H, respectively, in the frame of the machine, pinions G and F being 40 provided on said shafts and meshing with each other, one of the shafts, as D, being driven from a suitable source of power through the gear C, pinion B, driving-shaft A, and pulley X. The stock J to be drawn into wire 45 is fed between the grooves in rolls E and I and is thereby both drawn and fed forward to a revolving die L. The die L is secured in a suitable revolving carrier K, which is arranged adjacent the rolls E and I. Suitable

means are provided for rotating the carrier 50 K and die L, as shown in this instance, the carrier being provided with a hollow shaft or sleeve Q, supported in the frame of the machine and having a pulley R for rotating the same. The shoulders S of the die-carrier K 55 are provided, as shown, with ball-bearings to take up the end thrust or resist the endwise compression.

As shown in the drawings, the die-carrier K is also provided with a projecting portion 60 T, extending into close proximity to the rolls E and I and hollowed longitudinally for the passage of the stock to be drawn. The projecting portion T of the die-holder forms an antibuckling guide or support for the wire as 65 it comes from the rolls and guides the stock to the rotating die L. The die holder or carrier K is so constructed that dies of different size may be inserted therein, a portion W of the holder being removable and having a 70 spring-catch Y to adjust it in place.

Any suitable means may be provided for adjusting the height of one of the rolls, as shown in the drawings, there being adjustable vertical screws Z in the frame for varying the height of the upper roll.

As hereinbefore stated the metal of the stock is compressed between the rolls E and I before entering the rotary die, and the rolls also serve to feed the metal forward. The 80 stock is guided and supported between the rolls and the die by the guide T and is further reduced by passing through the revolving die L.

According to the construction shown the 85 speed of the rolls may be varied as desired, and the speed of rotation of the die and die-carrier may also be varied, so that any desired ratio may be obtained between these two speeds for the best working.

Obviously my invention may be embodied in widely-varying forms and some features of my invention may be used without others.

Therefore, without limiting myself to the construction shown and described nor enumerating equivalents, I claim, and desire to obtain by Letters Patent, the following:

1. In a wire-drawing machine, the combi-

nation of the die, means for revolving the same to obtain rotary movement between the die and the metal to be drawn, grooved rolls in advance of the die for compressing and 5 pushing the metal through the die, and means for positively rotating said rolls independent of the die and at desired speed with relation thereto, substantially as set forth.

2. In a wire-drawing machine the combination of a die and means for revolving the same to obtain a rotary movement between the metal to be drawn and the die, means for producing a compression of the metal on entering the die and antibuckling guides or 15 supports for the metal to be drawn, arranged adjacent the die, substantially as set forth.

3. In a wire-drawing machine the combination of a die and means for revolving the same to obtain a rotary movement between 20 the metal to be drawn and the die, means for producing a compression of the metal on entering the die and antibuckling guides or supports for the metal to be drawn, arranged between the said compressing means and the 25 die, substantially as set forth.

4. In a wire-drawing machine, the combination of grooved rolls for compressing and feeding the metal to be drawn, a die into which the compressed metal is fed from the rolls, means for positively rotating said rolls, 30 and independent means for rotating the die about the compressed metal at the desired speed, substantially as set forth.

5. In a wire-drawing machine, the combination of grooved rolls for compressing and 35 feeding the metal to be drawn, a die into which the compressed metal is fed from the rolls, an antibuckling guide or support between the rolls and die, means for positively rotating said rolls, and independent means 40 for rotating the die about the compressed metal substantially as set forth.

In testimony whereof I have signed this specification in the presence of two subscribing witnesses.

JOHN H. O'DONNELL.
